HULL CONSTRUCTION

Alphonse A. Dubay, Van Buren, Maine

Application October 10, 1939, Serial No. 298,835

1 Claim. (Cl. 114—62)

This invention relates to a hull construction for boats or ships and has for the primary object the provision of a device of this character, wherein the water resistance to the forward travel of the hull will be greatly reduced to permit faster speeds to be obtained without increasing the horsepower of the prime mover over that now employed in hulls of the conventional construction and to reduce to a minimum the size of the waves left to astern of the hull and which as their size increases due to present-day hull construction increases the drag on the forward progress of the hull in the water, the present construction tending to cause the hull to plane with less displacement of water and utilizing a major portion of the water displaced by its weight to raise the hull and in a forward direction to aid the prime mover in the propulsion of the hull through the water.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a bottom plan view illustrating a hull constructed in accordance with my invention.

Figure 2 is a side elevation illustrating the hull.

Figure 3 is a transverse sectional view taken on the line 3—3 of Figure 1.

Figure 4 is a transverse sectional view taken on the line 4—4 of Figure 1.

Figure 5 is a transverse sectional view taken on the line 5—5 of Figure 1.

Referring in detail to the drawings, the numeral 5 indicates the hull including the bottom 6, sides 7, a pointed bow 8 and a rounded or streamline stern 9. The bottom 6 is flat while the sides gradually converge toward the stern 9 from a point of the greatest width of the hull and also the sides gradually converge to the pointed bow 8 from a point of the hull's greatest width. The hull's greatest width is located well forward of midship. The bottom 6 substantially forward of the hull's greatest width has a slight upward curvature to the bow 8, as clearly shown in Figure 2 and indicated by the character A. The sharp bow 8 with the portion A of the bottom has a tendency to simply scrape the surface of the water. The bottom 6 being flat has a sled-like action upon the water with

the waterline on the hull reaching its greatest depth at a line perpendicular to the forward end of parallel keels 10 formed on said bottom and lying in close proximity to the sides. 5 The keels are parallel and have their forward ends located at approximately where the hull is of three-quarters of its total width or beam and terminate near the stern 9 in extremely close relation to the sides as will be apparent in Figure 1. The parallel keels so arranged on the flat bottom will trap therebetween the water that the hull tends to displace by its weight which trapped water has a raising effect upon the hull and in a forward direction. To facilitate the escape of the trapped water during the forward motion of the hull with the least resistance a spillway or cavity 11 is formed in the bottom 6 and arranged to parallel the longitudinal axis of the hull, the forward end of 15 the spillway or cavity being located slightly rearwardly of the forward ends of the keels with the rear end of said spillway opening outwardly through the stern 9 of the hull. The spillway or cavity gradually increases in width and depth 20 from its forward end to its rearward end which will permit the trapped water between the keels to escape from under the hull with the least amount of resistance and drag on the hull during its forward travel in the water. 25

Through the use of the flat bottom, parallel spaced keels and the spillway or cavity the hull may progress through the water much closer to the surface of the water than heretofore possible with the conventional type or shape of hull and 30 with the waves astern of the hull of a minimum size. The water trapped between the spaced parallel keels finding an escape through the spillway or cavity will rush upwardly therein thereby raising the hull in a forward direction toward 35 the surface of the water and escaping at the stern substantially in alignment with the longitudinal axis of the hull to permit the propellers of the hull to obtain a more efficient bite or traction in the water also providing for better 40 and more economical propulsion of the hull. 45

It is preferable that the bottom of the hull, outwardly of the keels have a slightly higher floor level than that portion of the bottom of 50 the hull confined between the keels which lessens the tendency of the hull to the greatest possible extent in the creating of undesirable waves to the astern of said hull.

Secured on the hull and within the spillway 55 is a cutwater strip or plate 13, the rear end of

which terminates rearwardly of the rear ends of the keels 10 and forms a mounting for a rudder 14, the latter being hinged on the strip or plate 13, as shown at 15. The portion of the plate or strip 13 projecting rearwardly of the rear ends of the keels 10 may have an opening 16 to allow water to pass from one side of said plate or strip to the opposite side thereof. The keels 10 may form shaft logs for propeller shafts 17 as clearly shown in Figures 2 and 3, the propellers being indicated by the character 18 and located at opposite sides of the plate or strip 13 slightly in advance of the opening 16. The forward portion of the strip or plate 13 tapers from its lower edge toward its upper edge as indicated in dotted lines in Figure 2 so as to offer the least amount of resistance to water passing through the spillway. The plate or strip 13 besides forming a mounting for the rudder also will act as an additional keel for the hull adjacent the stern thereof.

It is believed that the foregoing description, when taken in connection with the drawings will fully set forth the construction and advantages of this invention to those skilled in the art to 25

which such device relates, so that further detailed description will not be required.

Having thus described the invention, what I claim is:

- 5 In a boat construction, a hull including sides, a flat bottom, a pointed bow and a rounded stern, said hull having its greatest width forwardly of midship of said hull, parallel spaced keel members providing propeller shaft mountings secured on said bottom and located adjacent to the sides and extending from a point on said hull forwardly of the latter's greatest width to a point adjacent the stern for trapping water to permit the latter to have a buoying effect on the hull 10 for the elevation thereof with respect to the surface of the water, said bottom between said keel members formed to provide a cavity arranged in alignment with the longitudinal axis of the hull and opening outwardly through the stern thereby providing a water spillway, said cavity gradually increasing in depth and width from the forward end to the rear end thereof, and a longitudinally extending plate secured on the bottom within the cavity.

ALPHONSE A. DUBAY.
